Primary Examiner — Karen S Acker*Assistant Examiner* — Clare Ann Gannon(74) Attorney, Agent, or Firm — Thaddeus Ilg(57) CLAIM

The ornamental design for a towel with pockets, as shown and described.

DESCRIPTION

FIG. 1 is a front orthogonal view of a towel with pockets showing my new design;

FIG. 2 is a rear orthogonal view thereof;

FIG. 3 is a front view thereof shown hanging in a position of use; and,

FIG. 4 is a right side view thereof.

The broken lines showing a hook and phone in FIG. 3 represent environmental structure that forms no part of the claimed design.
